UNITED STATES PATENT OFFICE.

WILLIAM A. GILLENTINE, OF ARLINGTON, TEXAS.

PULLER.

Application filed January 12, 1925. Serial No. 2,007.

My present invention has reference to a tool for pulling terminals from the poles of storage batteries and incidentally for pulling bushings, timing gears and all other kinds of machinery from their bearings, and has for its object the provision of novel means for adjusting the tooth carrying arms of the device with respect to each other to effectively grip therebetween the battery terminal or other article to be pulled, and wherein the pulling action is effected by the contacting engagement of a longitudinally movable headed element with the pole of the battery or the support or bearing for other articles to be pulled.

A further object is the provision of a tool for this purpose constructed to provide a pair of oppositely disposed tooth carrying arms having forked ends for the reception of a block which is pivotally secured therebetween, means being provided for adjusting the arms with respect to each other so that the teeth of the arms may be moved toward each other to gripping position or readily released from such position, and wherein there is screwed through the block an element designed to contact with a rigid support, such for instance as the pole of a battery on which the terminal to be pulled is arranged, and wherein the rotation of the threaded element will draw on the arms to effect the pulling operation.

The invention further consists in other novel features of construction, combination and operative association of parts such as is disclosed by the drawings which accompany and which form part of this application.

In the drawings:

Figure 1 is a side elevation of the improvement.

Figure 2 is an edge view thereof.

Figure 3 is a sectional view on the line 3-3 of Figure 1.

Figure 4 is a side elevation with parts in section, illustrating the jaws on the arms engaging a bushing to be pulled.

Figure 5 is a side elevation showing the manner in which a sleeve is to be pulled.

Figure 6 is a fragmentary perspective view of the jaw end of one of the arms illustrated in Figure 5.

Figure 7 is a fragmentary elevation illustrating the manner in which the tool is employed for pulling a terminal from a battery pole.

Figure 8 is a similar view showing the manner in which the tool grips a corroded and frosted battery terminal.

As disclosed by the drawings I employ a pair of opposed arms 1 and 2 respectively. Preferably these arms are made up of two strips of metal, and each of the arms has its inner edge, adjacent to one of its ends, formed with one or more saw teeth which provide what may be termed jaws 3. The plates constituting the arms have their ends, opposite that provided with the jaws, bent outwardly and angularly to provide forks 4. The forked ends of the respective arms are arranged in lapping relation and are secured together by pivot means 5. These pivots also enter central openings in a cross sectionally rounded block 6 which provides the head of the tool.

The block 5 has a central threaded portion therethrough, arranged transversely with respect to its pivotal connection with the arms, and threaded through this opening there is a screw 7 having its outer end formed with a head 8, the said head being provided with oppositely extending arms 9 whereby the screw may be threaded through the block in either direction.

The screw has on its opposite end a head 10, and this head is designed to rest on a support, such as a conical element 11 on which a bushing 12 is wedged.

The arm 1 has its outer edge formed with a notch 13, and this notch is covered by a plate 14 secured on the said arm.

Pivotedly secured, as at 15, to the arm 2 there are the arms of a yoke 16. The yoke straddles the arms 1, 2, and the outer or connecting element of the yoke has a threaded opening therethrough. Screwed through this opening there is a threaded shank 17. The shank has an outer headed portion 18 and its inner portion is reduced, as at 19, to pass through an opening in the plate 14. The reduced portion 19 terminates in a head 20 which is received in the notch 13 of the arm 1.

It will be apparent that by screwing the headed element 17 in one direction, the arms 1 and 2 will be brought toward each other so that one of the toothed jaws 3 thereon will grip the lower edge of the bushing 12 and firmly sustain the tool on the bushing. The tool is further sustained by the contacting engagement of the swiveled head 10 with the element 11. By turning the screw

in one direction, the arms 1 and 2 will be drawn toward the headed end of the said screw and thereby easily extracting the bushing 12.

5 The construction illustrated in Figures 5 and 6 is similar to that previously described, except that the arms 1' and 2' have their outer ends formed with lateral extensions providing jaws 3'. These jaws may be 10 either inwardly or outwardly directed. When outwardly directed the jaws engage the lower edge of a sleeve or the like which is wedged in an opening therefor. The swiveled end of the head of the screw in 15 this instance, rests on a support 21. The sleeve is withdrawn by the turning of the screw.

So far I have described my improvement as a pulling device for bushings, sleeves or 20 the like, but it is to be understood that the improvement is essentially designed for pulling the lead terminals from the posts of storage batteries. These terminals are susceptible to disintegration by the battery 25 acid, so that the outer surfaces therof are frequently rendered uneven, and the said terminals become what is termed "frosted" on the poles or posts. There is no manner in which a tool can be inserted beneath the 30 terminals, but with my construction and as clearly illustrated in Figures 7 and 8 the toothed jaws on the arms of the improvement will bite into the sides of the terminals 20, regardless of the outer configuration 35 thereof, that is, regardless of the shape

of the terminal which has been partly eaten by the battery acid. This biting engagement insures the easy withdrawal of the terminals when the operating handle of the improvement is rotated and the swiveled 40 head rests on the outer end of the battery pole or post. This important function of the improvement will be appreciated by those skilled in the art to which my invention relates, and while I have herein set 45 forth a simple and satisfactory embodiment of my invention, I desire it to be understood that I am entitled to make such changes therefrom as fairly fall within the scope of what I claim.

Having described the invention, I claim:

A puller for the purpose described, comprising a pair of oppositely arranged arms having one or more saw toothed jaws adjacent one end thereof and having their opposite ends forked, a prong of each pair of forks overlapping the corresponding prong of the other pair, a block between the forked ends of the arms, pivots connecting the forks and securing the block therebetween, a headed screw threaded through the block, a head on the outer end of the screw, a yoke surrounding the arms and pivoted to one of said arms, and a screw member threaded through the yoke and swivelly engaging 60 with the free arm.

In testimony whereof I affix my signature.

WILLIAM A. GILLENTINE.
